UNITED STATES PATENT OFFICE.

WILLIS E. AUSTIN, OF MINNEAPOLIS, MINNESOTA; JOHN S. AUSTIN ADMINISTRATOR
OF SAID WILLIS E. AUSTIN, DECEASED.

PNEUMATIC ACTION FOR MUSICAL INSTRUMENTS.

Application filed October 5, 1917. Serial No. 194,864.

To all whom it may concern:

Be it known that I, WILLIS E. AUSTIN, a citizen of the United States, resident of Minneapolis, county of Hennepin, State of Minnesota, have invented certain new and useful Improvements in Pneumatic Actions for Musical Instruments, of which the following is a specification.

The object of my invention is to provide a pneumatic action particularly applicable to the type of musical instrument known as player piano which will dispense entirely with the use of bellows pneumatics or attached diaphragms and thereby eliminate the trouble and annoyance arising from the use of such devices and the expense and time required for renewing or replacing worn out parts.

A further object is to provide a pneumatic action for an instrument of this class constructed as a removable and separable unit, any number of which may be assembled or arranged in a group or bank as required for the size of the instrument to be operated, each unit being separately removable for examination or repairs without disturbing the other units of the group, and each unit having all of its moving parts retained in their respective positions in the device without the use of any permanent attaching means, whereby all of said parts are conveniently accessible for insertion or removal.

The invention consists generally in various constructions and combinations, all as hereinafter described and particularly pointed out in the claims.

The present invention is a modification and adaptation for player pianos of the essential features of the invention shown and described in my co-pending application, Serial No. 110,307, filed July 20th, 1916, which has matured into Letters Patent No. 1,295,672, issued February 25, 1919.

In the accompanying drawings forming part of this specification,

Figure 1 is a sectional view through a portion of the pneumatic action of a piano player, to which in this instance I have applied my invention,

Figure 2 is a similar view of one of the units of the action, illustrating the oscillating plate or piston of the motor in its raised position for operating the mechanism to strike the strings of the piano,

Figure 3 is a front elevation, partially in section, showing a transverse view of the motor chamber and the loosely mounted disc controlling the movement of a valve,

Figure 4 is a plan section, showing the position of the motor operating arms with respect to the stickers leading to the hammer actions of the piano,

Figure 5 is a detail sectional view, illustrating the motor parts separated,

Figure 6 is a detail sectional view on an enlarged scale of a modified construction of the disc casing,

Figure 7 is a plan view of the motor oscillating plate or piston.

In the drawings, 2 represents one of the motor frames, which is here shown as of substantially rectangular shape, and provided with a longitudinally extending recess forming a chamber 4, having inclined or beveled walls 6 extending across one end of the chamber (which for convenience I term the forward end), and along two of the sides thereof, the bevel decreasing and vanishing at the other or rear end of the chamber. The chamber 4 is also preferably of greater depth towards its forward end, and is open at one side, and a separable chamber section, or frame 3, is provided having a corresponding opening and formed interiorly with a beveled wall 6^a corresponding to the beveled wall 6 of the chamber 4.

A plate 8, provided with a flexible sheet 9 projecting beyond the edges of the plate (see Figure 7), fits within the opening of the chamber. The edge of the sheet 9, at one end of the plate, extends into a recess 7, in the upper surface of the frame section 3, where it is held between said section 3 and the edge of the motor frame 2. The remaining portion of the edge of the sheet 9 extends into the recess formed between the beveled wall 6 of the motor frame and the beveled wall 6^a of the section 3. The frame section 3 is secured to the motor frame 2 preferably by suitable screws 10. The part of the edge of the sheet 9 that lies in the recess 7 forms a hinge upon which the plate 8 with the attached sheet 9 oscillates, the edges of the sheet, except the part confined in the recess 7, turning in the groove or recess formed by the beveled walls 6, 6^a, of the motor frame and section 3.

By taking out the screws 10 the section

3 may be readily removed, and the oscillating plate or piston 8 may be taken out of the chamber 4, for inspection or repairs, and may as readily be restored to position, 5 and secured by putting back the screws 10.

An operating bar 11 is secured to the outer surface of the plate 8, preferably outside of the sheet 9. This bar extends downward and projects forward beyond the wall of 10 the motor frame, as illustrated in the drawings. Each of the operating bars 11 is adapted to engage and move a sticker bar 13, which, through devices well known in the construction of a player piano, leads to 15 means for operating the piano striking mechanism.

Each of the sticker bars, as here shown, is provided with an adjustable lug 12 which stands in the path of movement of the operating bar 11, so that when said bar is moved from the position shown in the lower part of Figure 1 to the position shown in the upper part of said figure, or in Figure 2, the corresponding sticker bar will be operated in a manner well understood in instruments of this type. I have shown in Figure 4 a series of the sticker bars 13, and two of the operating bars 11, illustrating their relation to said sticker bars. It 20 will be understood that one of the motor units will be provided for each sticker bar, and that the number of motor units required for any instrument will depend upon the 25 number of sticker bars with which the particular player piano is provided.

The rear portion of the motor frame has an upwardly extending, preferably rectangular, portion which I prefer to form as a separate block 2^a, and which is secured to the 40 motor frame 2, preferably by screws 30, which pass through an overlying plate 29, through the block 2^a, and into the upper portion of the motor frame 2. This construction is clearly illustrated in Figure 5, in 45 which the parts are shown separated one from another.

An exhaust or vacuum trunk 14 extends across the forward portion of all of the motor frames. A vacuum is continuously 50 maintained in this trunk by a suitable suction or pumping device (not shown).

I prefer to form the vacuum trunk 14 of substantially rectangular form in cross section, with an inturned flange 14^a at its lower 55 forward edge, adapted to be engaged by a projection 2^c on the upper forward edge of the motor frame 2. The vertical dimension of the exhaust trunk 14 preferably corresponds, substantially, to the like dimension 60 of the block 2^a, forming the upward rear projection on the motor frame, whereby the forward wall of the block 2^a and the rear wall of the vacuum trunk, when brought together, make a substantially close joint as indicated in Figures 1 and 2 and 4 of the

drawings. After the parts of the motor unit are assembled, or brought into the relation indicated in Figures 1 and 2 of the drawings, said motor units are secured to the vacuum trunk 14 by being placed side by 70 side, as indicated in Figure 3 of the drawings, with the projection 2^c on each unit engaging the flange 14^a on the vacuum trunk. Screws 28 are then inserted through opposing recesses 2^b, formed in the walls of the 75 blocks 2^a, the ends of said screws extending into the wall of the vacuum trunk 14, as illustrated in Figure 4 of the drawings.

It will be understood that any desired number of groups of said motor units may 80 be arranged in a bank, one horizontal group being arranged above another, as illustrated in Figure 3 of the drawings, and that a vacuum trunk 14 will be provided for each horizontal group of motor units. It will also be 85 understood that in vertical arrangement the units will be offset, or "break joints" thereby permitting a close spacing of the sticker bars 13 as indicated in Figure 4, and proper engagement thereof by the operating bars 11. 90

The upper surface of the block 2^a is provided with a chamber 22, which connects at one end with a passage 27 extending downward through the block 2^a and the motor frame 2, and connecting with the motor 95 chamber 4. The upper wall of the chamber 22 is preferably formed by the plate 29, and said plate is provided with a port 26. Beneath the port 26 and in line therewith is a port 23 leading from the chamber 22 into 100 a chamber 24^a preferably provided with a beveled lower wall 24^b. The chamber 24^a is connected by a port 24 with the interior of the vacuum trunk 14. Beneath the chamber 24^a is a recess 20 having a beveled wall, and a central well or depression 17, the beveled wall of the recess 20 standing opposite the beveled wall of the chamber 24^a. Arranged in the recess 20 is a flexible sheet 105 18, having secured thereto a disc 19, the diameter of which corresponds substantially to the diameter of the chamber 24^a. A duct 16 leads from the well 17, below the disc 18, preferably extending horizontally, then vertically in the block 2^a, and then horizontally 110 to the rear of the block 2^a, and communicating with a duct 16^a that is here shown as extending across the vacuum trunk 14. A tube 15 is connected with a port in the tracker bar (not shown) of the player piano 115 over which the roll of perforated paper passes. The tube 15 also connects with the duct 16^a, as shown in Figure 2 of the drawings. The end of the duct 16^a is preferably enlarged, so as to form a recess or small 120 chamber 16^b from which a fine opening or "bleed-hole" 25 extends into the vacuum trunk 14.

A valve 21, having downwardly extending guiding flanges 21^a, is arranged in the 125

chamber 22, beneath the port 26, with said guiding flanges extending downward through the port 23 into the chamber 24^a.

In Figure 6 I have shown the recess 20 cut or formed in the upper part of the frame 2, the flexible disc 18 being inserted therein by folding inward its edges.

Operation.

10 It will be understood that in the operation of pneumatically actuated player pianos, the piano is operated each time a perforation in the perforated sheet passes the corresponding controlling port or duct on 15 the tracker bar. In the device herein shown and described the tube 15, leading from the tracker bar, will be closed or sealed so long as an imperforate portion of the perforated sheet is passing over the corresponding port 20 or duct. When a perforation passes over such port or duct air will be permitted to enter the corresponding tube 15, and pass therethrough and into the corresponding duct 16^a.

25 Assuming that the port on the tracker bar communicating with the tube 15 of the motor unit, shown at the lower portion of Figure 1 of the drawings, is closed or sealed, the parts will then stand in the position shown 30 in the lower part of Figure 1 of the drawings. The suction from the vacuum or exhaust trunk 14 will create a vacuum in the well or depression 17 beneath the flexible disc 18, and also in the chamber 24^a. The 35 air from the depression 17 will be drawn into the vacuum trunk 14 through the duct 16, the chamber 16^b, and the bleed-hole 25, while the air from the chamber 24^a will be exhausted through the port 24. Atmospheric 40 pressure upon the valve 21 will hold it in its lowest position, closing the port 23. Air will now enter the motor chamber 4, through the port 26, the chamber 22 and the 45 passage 27, and the oscillating plate or piston 8 will stand in its lowermost position, with the edge of the sheet 9 against the beveled wall 6^a of the section 3. As soon, however, as air is permitted to enter the tube 15, through the passage of a perforation in the 50 control sheet over the port in the tracker bar communicating with such tube 15, such air will pass freely through the duct 16 into the recess 17 beneath the flexible sheet 18, and the suction, from the vacuum trunk 14,

55 will raise the valve 21, because the area of said valve is less than the area of the sheet 18, and the parts will now stand in the position shown in the upper part of Figure 1, with the port 26 closed by the valve 21. The 60 air will be exhausted from the motor chamber 4 through the passage 27, the chamber 22, the port 23, the chamber 24^a and the port 24, and the oscillating plate or piston 8 will 65 instantly be thrown upward, from the position shown in the lower part of Figure 1, to

the position shown in the upper part of Figure 1, and also shown in Figure 2. This movement of the oscillating plate or piston 8 will, through the operating bar 11, and the sticker bar 13 operate the striker mechanism 70 of the piano. As soon as the passage of air to the tube is cut off by an imperforate portion of the control sheet of the piano player, the air will be exhausted from the well or depression 17 through the duct 16, the chamber 16^b, and the bleed-hole 25, and the valve 21 will drop from the position shown in the upper part of Figure 1 of the drawings to the position shown in the lower part of said figure. Air will then pass freely through 80 the port 26, the chamber 22 and the passage 27 to the chamber 4 and the oscillating plate or piston 8 will immediately drop to the position shown in the lower part of Figure 1 in the drawings. These operations will be 85 repeated so long as the perforated sheet is passed over the tracker bar.

It will be seen that I do away with the usual bellows-pneumatic in which flexible bellows walls are permanently secured to 90 rigid walls. Such flexible walls are liable to become cracked and broken and are difficult of repair. In my device the flexible sheet 9 of the motor, and the flexible disc 18 below the valve 21, which are the only parts that 95 are at all liable to need replacement, may be quickly removed and replaced, and every part of the entire device is readily accessible and removable for inspection or repairs.

The motor chamber 4 is quite shallow and 100 the air may be almost instantly exhausted therefrom, thus producing a very quick, rapid upward movement of the movable plate or oscillating piston 8 and a correspondingly rapid movement of the sticker 105 bar that is moved by said piston.

From the foregoing description it will be noted that I am able to provide a pneumatic action which will be positive and reliable in its movement, comparatively simple in construction and will dispense entirely with attached diaphragms, bellows-pneumatic and the like.

I do not limit myself to the details of the construction herein shown and described, as 115 the same may be varied in many particulars without departing from my invention.

I claim as my invention:

1. In a pneumatic action for musical instruments, the combination, with a motor 120 chamber having an open wall, of a movable member arranged to close the opening in said wall and provided with a flexible sheet bearing to bear against the wall of said chamber, said flexible sheet being free and 125 unattached except to the movable member, an operating bar secured to said movable member, and means for alternately exhausting the air from said chamber, and permitting it to re-enter therein.

2. In a pneumatic action for player pianos, the combination, with a motor chamber having an open wall, of a movable member arranged to close the opening in said wall and provided with a flexible sheet projecting from the edges of said member, and disposed to bear against the wall of said chamber, said flexible sheet being free and unattached except to the movable member, 5 and provided with a sticker operating bar secured to and projecting from said movable member, and means for alternately exhausting the air from said chamber and permitting it to re-enter therein.
- 10 3. In a pneumatic action for played pianos, the combination, with a motor chamber having an open wall, of an oscillating plate or piston arranged to close said opening, and provided with a flexible sheet disposed to bear against the wall of said chamber, said flexible sheet being free and unattached except to the plate, an operating bar secured to said plate, an exhaust trunk, and a valve controlled passage permitting air to be exhausted from said chamber by means of said trunk, and to re-enter said chamber, where by an oscillating movement of said plate or piston is produced.
- 15 4. In a pneumatic action for player pianos, the combination, with a motor chamber, having an open wall, of a movable member arranged to close the opening in said wall and provided with a flexible sheet projecting from the edges of said member, said flexible sheet, at one end of the movable member, extending into a recess at the end of the chamber and forming a hinge upon which said member may oscillate, the remaining portion of the edge of said sheet being disposed in said beveled recess and disposed to bear against the walls thereof, said sheet being free and unattached except to the movable member.
- 20 5. In a pneumatic action for player pianos, the combination, with a motor chamber having an open wall, of a frame section secured to the wall of said chamber around said opening, a beveled recess being formed between the wall of the chamber and the frame section across one end of the chamber and along each side thereof, said recess along the sides of the chamber decreasing progressively and vanishing near the end of the chamber, a movable member arranged to close the opening in said wall and provided with a flexible sheet projecting from the edges of said member, said flexible sheet, at one end of the movable member, extending into a recess at the end of the chamber and forming a hinge upon which said member may oscillate, the remaining portion of the edge of said sheet being disposed in said beveled recess and disposed to bear against the walls thereof, said sheet being free and unattached except to the movable member.
- 25 6. In witness whereof, I have hereunto set my hand this 18th day of September 1917.
- 70 WILLIS E. AUSTIN.
